UNITED STATES PATENT OFFICE.

SAMUEL B. WILLIAMS, JR., OF BROOKLYN, AND EDWARD E. HINRICHSEN, OF NEW YORK, N. Y., ASSIGNORS TO WESTERN ELECTRIC COMPANY, INCORPORATED, OF NEW YORK, N. Y., A CORPORATION OF NEW YORK.

TELEPHONE SYSTEM.

Application filed May 14, 1921. Serial No. 469,650.

To all whom it may concern:

Be it known that we, SAMUEL B. WILLIAMS, Jr., and EDWARD E. HINRICHSEN, citizens of the United States, residing at 5 Brooklyn, in the county of Kings, State of New York, and at New York, in the county of New York, State of New York, respectively, have invented certain new and useful Improvements in Telephone Systems, of 10 which the following is a full, clear, concise, and exact description.

This invention relates to improvements in telephone systems and has particular reference to a private branch exchange system which may be used in conjunction with either manual or machine switching central 15 offices.

An object of the invention is the provision of an automatic switch wherein novel 20 means are employed for preventing response of the switch to false impulses produced sometimes by the accidental depression of the switchhook.

In accordance with the above object, use 25 is preferably made of a relay in the switch circuit the operation of which is so controlled that when the first of a series of impulses is transmitted to a switch, said relay will prevent the stepping of the 30 brushes of the switch until the second impulse is received, whereupon the relay operates to allow the switch to respond to said second and subsequent impulses.

Another object is to provide novel means 35 which will permit an attendant to secure a connection to a subscriber's line through a connector switch on a call incoming from a central office even though said line be busy.

A further object is the provision of a 40 ringing circuit for a connector switch wherein a ringing tone is transmitted to a calling subscriber when a called subscriber is being signaled and wherein a premature application of said ringing tone is prevented while the switch is being moved over terminals individual to subscribers' 45 lines in different groups.

Other objects will appear in the course 50 of the following description when taken in connection with the accompanying drawings wherein Figures 1 to 6, when taken together and arranged as shown in Figure 7, diagrammatically illustrate a preferred embodiment of the inventive idea.

Briefly stated, the invention provides a 55 private branch exchange in which line finder switches are employed for extending calling subscribers' lines over link circuits to selector switches. These latter switches have access to connectors for establishing 60 calls between subscribers within the exchange; and also to attendant's and central office trunks, whereby subscribers may secure connection with an attendant or a direct connection to a central office. The terminals assigned to the various connectors and trunks in the bank of each selector may be arranged in any desired manner, means being provided in the switch for stepping 65 the brushes thereof over undesired terminals 70 when seeking terminals individual to idle connectors, attendant's trunks or central office trunks.

An incoming call from central office to a subscriber within the exchange is routed 75 through the attendant who connects the central office trunk to an idle connector and then operates the latter by dial impulses to 80 select a desired line. If this line is busy, the attendant may nevertheless obtain connection thereto by the operation of a key in the central office trunk.

An attendant may originate a call to the subscriber within the exchange or she may initiate a call to central office and, if desired, extend it to a station in the same manner that an incoming call from the central office is extended thereto.

The trunks leading to the central office may terminate in a manual exchange or in 90 a machine switching office and, in the latter instance, provision is made whereby the attendant may have supervision over certain connections such as when a toll call is initiated. For this purpose, use is preferably 95 made of a code switch, shown in Figure 6, which upon the seizure of a central office trunk by a calling subscriber establishes a condition whereby, when impulses are transmitted by said subscriber, said impulses will 100 operate the code switch and be simultaneously repeated at the central office to actuate the switches thereat. The code switch, in this operation, discriminates between the character of calls initiated by subscribers 105 by setting up certain conditions in the circuit of the switch in response to the impulses transmitted. If a call is such as to

require supervision by the attendant, discriminating relays in the code circuit operate in response to the dial operations to effect a condition whereby a signal before the attendant's position individual to the seized trunk will be operated. On the other hand, if the call does not require supervision, the code switch will nevertheless operate, but the discriminating relays will fail to establish the condition which causes the operation of the signal at the attendant's position.

It is believed that the invention will now be fully understood from the following detailed description of the operation in establishing various connections.

Assuming that the link circuit L, shown in Figure 1, is the first idle link circuit to which the calling lines of a group have access, when a subscriber at substation A initiates a call, a line relay 100 individual to the calling line is energized over a path extending from battery through the winding of said relay, the back contact and left-hand armature of cut-off relay 101, the apparatus at substation A and the outer right-hand armature and back contact of relay 101 to ground. The energization of line relay 100 closes a circuit for the relay 102 of the line finder switch B associated with the link circuit L, said circuit extending from grounded battery through the winding of relay 102, the brush 103 of the line finder, back contact and inner left-hand armature of relay 104, conductor 119, the front contact and armature of line relay 100 and from thence over the common conductor 105 to ground at relay 106. The energization of relay 102 establishes an obvious circuit for slow to release relay 107, whereupon an energizing circuit for the motor magnet 108 of the line finder is closed, said circuit extending from grounded battery through the winding, armature and back contact of the magnet 108, the inner left-hand armature and front contact of relay 102, the left-hand armature and front contact of relay 107, brush 109 of the selector switch C and its associated normal contact, the back contact and outer left-hand armature of relay 104 and the left-hand normal contacts of slow to release relay 110 to ground. At the same time, a circuit is established extending from grounded battery through the left-hand winding of relay 111, the winding of relay 112, the outer right-hand armature and back contact of relay 104, the front contact and right-hand armature of relay 107, and from thence over the energizing circuit of relay 102 through the brush 103 to ground. Relays 111 and 112 energize, but the operation of relay 111 at this time has no useful function. The energization of relay 112 disconnects the battery supply through the windings of the line relay 113 from the

brushes 114 and 115 of the line finder. The stepping magnet 108 is operated by the circuit described therefor and the brushes of the line finder are stepped from their normal positions. Upon leaving these positions the operating circuits for relays 102 and 112 are opened at the brush 103 but said relays are maintained energized during the stepping operation of the line finder due to a holding circuit extending through the front contact and inner right-hand armature of relay 102 to brush 116 of the line finder to back contacts of the line relays of the lines connected to terminals over which said brush passes. The circuit of the stepping magnet 108 being self-interrupting, the line finder will continue to step as long as brush 116 encounters ground on the terminals over which it passes. When the terminal of the calling line is reached no ground will be found upon that terminal engaged by brush 116 due to the fact that the line relay 100 is operated. Relays 102, 111 and 112 will therefore release as the holding circuit for these relays is no longer closed. The release of relay 102 permanently opens the circuit of the stepping magnet 108 and the brushes of the line finder come to rest upon the terminals of the calling line. A circuit is now established for the cut-off relay 101 of said line extending from grounded battery through the winding of said relay, the sleeve brush 117 and its associated terminal and the back contact and outer left-hand armature of relay 102 to ground. Relay 101 operates and thereby opens the energizing circuit for relay 100 which then restores. The ground from the outer left-hand armature and back contact of relay 102 is extended to the test terminal 118 of the calling line and causes this line to test busy if engaged by the test brush of a connector switch. The release of relay 112 establishes a circuit for relay 113 traceable from grounded battery through the left-hand winding of relay 113, back contact and outer left-hand armature of relay 112, brush 114 and its associated terminal, the calling substation line circuit, the brush 115 and its associated terminal, the inner left-hand armature and back contact and relay 112 and the right-hand winding of relay 113 to ground. Relay 113 energizes in the circuit described therefor and establishes an obvious operating circuit for slow to release relay 110. Upon the energization of the latter relay, a circuit is closed for relay 104 extending from grounded battery through the right-hand winding of said relay 104, the outer right-hand armature and back contact of relay 102, the left-hand armature and front contact of relay 110 to ground. The energization of relay 104 in the circuit just traced disconnects the common lead 119 from the inner left-hand back contact of

relay 104 so that a second call initiated in the group of which line A forms a part will be extended through the inner left-hand armature and back contact of the relay 104 of the next idle line finder to the normal terminal of said finder engaged by brush 103. The release of relay 102 at the time the brushes of the line finder engage the terminals of the calling line also causes the release of relay 107, but, owing to the slow release nature of the latter relay, the circuits for relays 104, 110 and 113 are established before relay 107 retracts its armatures. This is for the purpose of preventing premature release of the line finder as will be more fully understood in the course of the following description. A dial tone from the apparatus 120 is now connected to the calling line through the brushes 121 and 122 of the selector switch and their associated normal contacts. Upon hearing this tone, the subscriber may proceed to dial the number desired.

A connection from a subscriber at substation A to another subscriber within the private branch exchange, such as the one at substation D (Figure 2), will first be described. The subscribers in the private branch exchange are divided into two groups each of which is served by a group of connectors. In the case of one group of subscribers, the first digit of numbers in the group is always 8 while the first digit of numbers in the second group is always 9. It will be assumed that the subscriber D is in the first group and it will, therefore, be necessary to dial 8 as the first digit.

Before proceeding with the description of this connection, it is to be noted that, for purpose of simplicity and economy of space, several of the terminals in the bank of the selector C have been omitted. As shown, there is provided a normal terminal followed by three terminals that are allotted for central office trunks. The next two terminals are assigned to connectors employed in establishing connections between the two groups of subscribers within the exchange. However, between these two sets of terminals other terminals allotted for central office selection may be provided and in accordance with the following description there are three more terminals to which central office trunks may be connected. The system thus makes provision for six central office trunks, the terminals for three of which are shown. The next two terminals shown in the selector bank following those allotted to connectors are assigned to attendant's trunks and the succeeding terminals, with the exception of the last, are also allotted to the groups of connectors employed to establish connections within the exchange. The terminals of the two groups of connectors are preferably arranged alter-

nately and provision is made whereby only an idle connector assigned to the group of lines in which the called line is located will be selected, the terminals of the connectors serving the other group of lines being automatically passed over in the selection of said idle connector. It will be understood, of course, that the number of connectors and trunks to the central office depend solely upon the size of the exchange and may vary without departing from the spirit or scope of the invention.

Proceeding now with the description of the above noted connection and taking up the operation from the point where relay 110 is operated by the energization of relay 113, a circuit is now established from grounded battery through the resistance 126, the left-hand winding of the stepping relay 127, the brush 125, right-hand normal contacts of relay 128 and the right-hand armature and front contact of relay 110 to ground. Relay 127, however, does not operate in this circuit due to the ground extending from the right-hand armature of relay 110 through the right-hand armature and front contact of relay 113, the outer right-hand armature and back contact of relay 129, the brush 124 to the left-hand winding of relay 127. This ground short circuits the relay 127 and prevents the same from operating until the impulse receiving relay 113 releases in response to the impulses transmitted from the calling substation.

Upon the release of relay 113 in response to the first impulse transmitted, relay 127 energizes and thereby establishes an obvious circuit for operating slow to release relay 130. The energization of the latter relay causes the operation of relay 129 to disconnect the brushes 121 and 122 of selector C from the remaining portion of the link circuit, the circuit for relay 129 being traceable from grounded battery through the left-hand winding of said relay, the left-hand front contact and armature of relay 130 and the right-hand armature and front contact of relay 110 to ground. The right-hand contact of relay 113 is now connected, by the operation of relay 129, directly to the resistance 126 instead of being extended through the brush 124. The operation of relay 130 also establishes an energizing circuit for relay 128 which extends from grounded battery through the winding of relay 128 and the right-hand armatures and front contacts of relays 130 and 110 to ground. However, relay 128 does not energize at this time due to a short circuit provided by ground at the left-hand armature of relay 127 and extending through the inner left-hand armature and back contact of relay 128. The circuit for motor magnet 131 of the selector C extends through the front contact and inner left-

hand armature of relay 128, but inasmuch as this relay does not energize at this time it is apparent that the motor magnet will not operate to step the switch from its normal position in response to the first impulse transmitted. Thus relay 128 delays placing the operating mechanism of the selector switch under the control of the stepping relay 128 until the end of the first selecting 5 impulse so that the switch takes its first step in response to the second impulse of a series. Therefore, should a false impulse be transmitted to the switch by the calling subscriber accidentally depressing the switch hook, or otherwise, the switch will not respond to this impulse nor to any other false impulse transmitted before the dial at the substation is operated. When relay 113 operates at the termination of the first impulse, relay 127 is again short circuited and 10 releases. This permits relay 128 to operate over the energizing circuit described therefor and in so doing said relay places the motor magnet 131 under the control of relay 127. The operation of relay 128 also connects the operating winding of relay 127 direct to ground through the right-hand armature and front contact of relay 110 instead of through the brush 125. The next 15 release of relay 113 in response to the second impulse permits relay 127 to operate thus connecting the ground at relay 127 to the winding of motor magnet 131. Relay 127 is locked up through its right-hand contact and armature, the contact and armature of motor magnet 131, the front contact and inner left-hand armature of relay 128, which 20 now remains operated, and the front contact and left-hand armature of relay 127 to ground. The construction of the motor magnet 131 is such that its contact and armature are not separated until the motor magnet has completed its stroke and therefore relay 127 will remain locked until such 25 time that said armature and contact are separated notwithstanding the fact that the short circuit for the left-hand winding of relay 127 may be closed by the operation of relay 113 before the motor magnet advances the brushes of selector C to the second terminals associated with said brushes. In 30 response to the further impulses the switches advance in the same manner as just described until the brush 125 engages the terminal 132 and the remaining brushes of the switch engage associated terminals located in the same vertical row with the terminal 132. It is to be noted that during the transmission of impulses relays 110 and 130 remain operated, due to their slow to release 35 nature, while the circuits therefor are being momentarily interrupted. After the last impulse, relay 113 remains operated whereupon relay 127 releases thereby causing, after an interval, the release of relay

130. The deenergization of the latter relay opens the circuit for relay 128 which also releases.

The brushes of the switch are now engaged with terminals assigned to the first connector of the first group which is employed for establishing connections to the called lines served by said group of connectors. If this first connector is busy this condition is denoted by ground upon the 70 terminal engaged by brush 123 of the selector and relay 129 will therefore remain operated and cause the operation of relay 133 over a circuit extending from grounded battery through the left-hand winding of relay 129, left-hand normal contacts of relay 130, the right-hand winding of relay 133, the front contact and inner right-hand armature of relay 129 and the brush 123 to ground. Also, the release of relay 128 connects ground at the right-hand normal contacts of relay 128 to brush 125 and terminal 132 and from thence through the inner right-hand armature and back contact of relay 111 and winding of relay 134 to 80 ground. Relay 134 energizes and establishes an operating circuit for relay 135 extending from grounded battery through the winding of relay 135, the front contact and inner right-hand armature of 85 relay 134, the right-hand normal contacts of relay 130 and the right-hand armature and contact of relay 110 to ground. Both relays 134 and 135 lock up through their front contacts and inner left-hand armatures and from thence over the energizing circuit of relay 135. The operation of relay 134 disconnects the first of the terminals assigned to the second group of connectors, that is the terminal following terminal 132, 90 from the winding of relay 135 and connects said terminal to the right-hand winding of relay 129 and the left-hand winding of relay 133 in parallel. The operation of relay 135 establishes a self-interrupting circuit for 95 motor magnet 131 extending from ground through the outer left-hand armature and front contact of relay 135 and the left-hand inner armature and front contact of relay 133 and the contact, armature and winding 100 of motor magnet 131 to grounded battery, thus causing said motor magnet to operate and advance the brush 125 of the switch from terminal 132 to the next succeeding terminal. Inasmuch as the relay 134 is now 105 operated the ground on the brush 125 will be extended through the outer right-hand armature and front contact of relay 134 to the right-hand winding of relay 129 and the left-hand winding of relay 133 to maintain these two relays energized whereby the motor magnet 131 will be caused to advance the brushes of the switch another step. This 110 engages the brush 125 with the first of the two terminals 137 allotted to attendant's 115 120 125 130

- trunks and the ground on brush 125 will then be extended through the inner right-hand armature and front contact of relay 135, the left-hand armature and back contact of relay 138 to the before-mentioned windings of relays 129 and 133. The switch therefore continues to step over the terminals assigned to attendant's trunks until the next succeeding terminal is reached which is the one allotted to the second connector of the group serving the group of lines in which the called line is located. If this second connector is also busy, the relays 129 and 133 will not be maintained energized through the brush 125 since the terminal, following the second terminal 137, is not connected to the right and left-hand windings of said relays, respectively, due to the fact that the outer right-hand armature of relay 134 is separated from its back contact. However, relays 129 and 133 will remain energized through the brush 123 which finds ground at the busy connector. The motor magnet 131 will therefore advance the brushes of the switch C to engage the next succeeding terminal. The brushes of the switch will therefore be again advanced and this operation will continue until the terminals of an idle connector in the first group are located. When this occurs ground will no longer be connected to either of the windings of either of the relays 129 and 133 and these relays will therefore release. Inasmuch as relay 112 is not operated, relay 113 remains under the control of the calling subscriber and relay 110 is maintained operated. It will be recalled that the operating circuit of relay 127 is removed from control of brush 125 when the selector takes its initial step and from the control of relay 128 at the termination of the first series of impulses. Therefore, the relay 127 and consequently the selector switch will not respond to any further impulses transmitted. Upon the release of relay 129 after the selection of the trunk leading to the idle connector, and assuming this connector to be the one to which terminal 136 is assigned, ground is extended to the connector through the right-hand armature of relay 110, the right-hand armature and contact of relay 113, the outer right-hand armature and back contact of relay 129 and the brush 124. Ground is also connected to the brush 123 from the left-hand armature and front contact of relay 110, the inner right-hand armature and front contact of relay 104, and the back contact and inner right-hand armature of relay 129. With the brushes of the selector C in engagement with the terminals of the trunk extending to the idle connector switch E shown in Figure 2, the relay 200 of the switch E operates over a circuit extending from grounded battery through the wind-
- ing of said relay, the brush 201 and its normal terminal and the conductor 202 to above mentioned ground on the brush 123. Relay 200 operates and locks through its outer left-hand armature and front contact to ground on the conductor 202. The operation of relay 200 establishes an operating circuit for stepping relay 203 extending from grounded battery through the resistance 219, the left-hand winding of said relay, the brush 204 and its associated normal contact, the right-hand normal contacts of the slow to release relay 205 and the front contact and inner right-hand armature of relay 200 to ground. Relay 203, however, does not operate due to the short circuit established by the ground extending from brush 124 of the selector to the conductor 206, the application of this ground being controlled by the relay 113. The ground extended from the outer right-hand armature and front contact of relay 200, upon the operation of the latter relay, is applied to the brush 207 of switch E through the normal contact and outer right-hand armature of relay 208 and is connected to the right-hand winding of slow to release relay 209 which thereupon operates to disconnect the source of ringing current 210 from the brushes 211 and 212 of the connector. Relay 209, by operating, also prevents the transmission of a ringing tone to the calling subscriber's line through the back contact and inner left-hand armature of relay 209, the back contacts and outer left-hand armatures of relays 208 and 215, the condenser 218, and the back contact and outer left-hand armature of relay 216. The connector switch is now ready to receive impulses transmitted from the calling station and upon each deenergization of the relay 113, in response to said impulses, the short circuit for the left-hand winding of relay 203 is removed and said relay operates and locks through its front contact and inner right-hand armature and the contact and armature of the motor magnet 213. As described in connection with the relay 127 of the selector switch, the locking circuit for relay 203 remains closed until the motor magnet has completed its stroke.
- The second digit of the numbers of the subscribers within the exchange is either 1 or 0 and in the establishment of the connection shown in Figure 2, the subscriber's line D is shown in the group of lines having 0 as the second digit. For the same reason as referred to in connection with the terminal bank of selector C, a number of the terminals of the bank of switch E have been omitted. By referring to the row of terminals associated with brush 204, it will be seen that only two terminals are shown to indicate the group of subscribers' lines, the second digit of which is 1. These terminals

follow the second or intermediate terminal associated with the brush 204 which engages said second terminal when one impulse is transmitted to the selector switch. The terminal in the row referred to following the last terminal assigned to the subscribers' lines in the first group is the next intermediate terminal upon which the brush 204 comes to rest when ten impulses are transmitted to the connector switch. Following this terminal are others assigned to the second group of subscribers' lines having 0 for the second digit. As shown in the drawing, the subscriber's line D is associated with the first vertical row of terminals in the second group of subscribers' lines and therefore in order to secure connection to this line, it will be necessary to dial 0 and 1 as the second and third digits of the called line. Each operation of the motor magnet 213 in response to the energization of relay 203 advances the brushes of the switch E over the associated terminals until the brushes engage the vertical row of terminals in which the terminal 214 is located. The first operation of relay 203 establishes an energizing circuit for relay 205 which remains operated during transmission of impulses from the calling substation. The operation of the relay 205 establishes a circuit for relay 208 extending from grounded battery through the left-hand winding of relay 208, front contact and left-hand armature of relay 205, and the front contact and outer left-hand armature of relay 200 to ground on the conductor 202. Relay 208 operates and disconnects the trunk from the brushes 211 and 212 and also opens, at its outer right-hand armature and back contact, the energizing circuit for relay 209 which thereupon releases. During the transmission of impulses, the dial at the calling substation opens the receiver circuit and hence the calling subscriber will not hear the ringing tone while the dial is operating and the relay 209 is released. The operation of relay 205 disconnects the ground at relay 200 from the brush 204 and connects said ground through the front contact and right-hand armature of relay 205 directly to the left-hand winding of stepping relay 203, so that the operating circuit of the latter relay will not be open when the switch moves from its normal position.

At the termination of the first series of impulses, relay 203 remains deenergized sufficiently long to permit the release of relay 205. Brush 207 is now engaged with an intermediate terminal of its associated row. The restoration of the latter relay opens the energizing circuit for relay 208 which thereupon releases. Ground is again connected to brush 207 through contacts of relays 200 and 208 whereupon relay 209 again operates through its right-hand wind-

ing to again prevent the application of ringing tone to the calling line. The release of relay 205 again closes the operating circuit for stepping relay 203 through the brush 204 and terminal 214. It will thus be seen from the foregoing description, that while the brushes of the switch are in engagement with either the normal or intermediate terminals, ringing tone is disconnected from the calling subscriber's line by the operation of relay 209.

The impulses are now transmitted corresponding to the last digit of the called number and in the example shown, its digit being 1, the brushes of the switch are stepped in the same manner as previously described to engage the terminals individual to the called line. Relay 208 is again operated upon the first operation of relay 203 to open the circuit for relay 209 which releases before the magnet 213 can step the brushes of the switch onto the next set of terminals. If the line is busy, the release of relay 205 at the termination of the impulses transmitted establishes a circuit extending from grounded battery through the left hand winding of relay 208, the left-hand normal contacts of the relay 205, winding and inner left-hand normal contacts of the relay 215, the inner left-hand armature and front contact of relay 200, the front contact and outer right-hand armature of relay 208 to the brush 207. The busy condition of the called line is denoted by ground upon the terminals associated with the brush 207, such as the terminal 118, of Figure 1, and this ground causes the relay 208 to remain operated and relay 215 to energize. A holding circuit is established for relays 208 and 215 by the operation of the latter, said circuit extending through the front contact and inner left-hand armature of relay 215, the right-hand normal contacts of relay 216 and the front contact and outer right-hand armature of relay 200 to ground. Relay 209 is not operated at this time since its right-hand winding is not connected to the terminal engaged by the brush 207. However, the operation of relay 208 prevents the application of ringing current to the called line and ringing tone to the calling line. The operation of relay 215 connects the busy tone apparatus 217 through the front contact and outer right-hand armature of said relay, the condenser 218 and the back contact and outer left-hand armature of relay 216 to the tip side of the trunk and from thence to the calling subscriber's line. The subscriber, upon hearing this tone replaces his receiver on the switch hook to restore the apparatus to normal in a manner which will presently be described. At the time of the application of the busy tone, a circuit is closed for relay 216 extending from grounded bat-

tery through resistance 219 at relay 203, winding of relay 216, front contact and inner right-hand armature of relay 215, brush 204, the right-hand normal contacts of relay 205 and the front contact and inner right-hand armature of relay 200 to ground. Relay 216 does not operate at this time due to the ground on the conductor 206 which is connected to the brush 204 of the selector, this ground short circuiting the relay 216.

Assuming now that the called line is not busy, the relay 215 fails to operate and relay 208 releases due to the lack of ground on the brush 207. The release of relay 208 connects ground through its back contact and outer right-hand armature from the relay 200 to the brush 207 and this ground extends through the winding of the cut-off relay 220 of the called line which thereupon operates. The multiple test terminals of the called line, similar to the terminal 118, are now grounded and will test busy to any other connector switch engaged therewith. Due to the fact that relay 215 does not operate when the terminals of the idle line are engaged, a circuit is established from relay 221 extending from grounded battery through the winding of said relay, the right-hand armature and back contact of relay 209, the back contact and inner right-hand armature of relay 215, the brush 204, the right-hand normal contact of relay 205 to ground at the inner right-hand armature and front contact of relay 200. The relay 221 is similar to relay 433 shown in the co-pending application of Edward E. Hinrichsen, filed July 14, 1920 and bearing Serial No. 396,143. Said relay is designed to control the generation of ringing current in the source 210 in the manner described in said co-pending application and this source of ringing current is thereupon connected through the left-hand winding of relay 209 to the substation apparatus of the called line through back contacts of relays 209 and 208 and the brushes 211 and 212. A portion of this ringing current is diverted through the outer left-hand armatures and back contacts of relays 215 and 216 and condenser 218 to the calling line to notify the subscriber thereat that the called line is being signaled. When the called subscriber removes his receiver from its switch hook, sufficient current passes through the left-hand winding of relay 209 to operate the same and said relay thereupon locks up to ground on conductor 202 through brush 201 and the front contact and inner right-hand armature of said relay. The operation of relay 209 disconnects ringing current from the called line and connects said line to the calling line through the selector switch C. The calling line is now supplied with talking current from the relay 113 and the called line has talking

current connected thereto from relay 138 through the right-hand normal contacts of relay 112. Conversation may now proceed between the subscribers at substations A and D.

At the termination of the conversation, the replacing of the receiver upon its switch hook at the calling substation releases relay 113, whereupon relay 110 deenergizes. The restoration of the latter relay opens the energizing circuit for relay 104 extending through the left-hand armature and front contact of relay 110 and the outer right-hand armature and back contact of relay 102. Ground from the left-hand normal contacts of relay 110, the outer left-hand armature and back contact of relay 104 and brush 109 of the selector is now extended in parallel to the right and left-hand windings respectively of relays 129 and 133 and said relays thereupon operate. Upon the operation of relay 133, a circuit is established from ground through the right-hand normal contacts of relay 110, the inner left-hand armature and front contact of relay 133, the contact, armature and winding of motor magnet 131 of the selector to grounded battery. This is a self-interrupting circuit and upon each closure thereof, the motor magnet operates to step the brushes of the switch until the same are returned to normal when the circuit for relays 129 and 133 is opened at the brush 109. The release of relay 133 permanently opens the operating circuit for the motor magnet and the brushes of the selector switch come to rest upon their normal terminals. The release of relay 110 also opens the locking circuits for relays 134 and 135 which thereupon restore to normal.

A circuit is now established for relay 102 extending from grounded battery through the winding of said relay, the brush 103 of the line finder, the left-hand normal contacts of relay 107, brush 109 and its normal terminal, the back contact and outer left-hand armature of relay 104 and from thence to ground at relay 110. Relay 102 energizes in this circuit and locks through its front contact and inner right-hand armature to the brush 116, and the terminal of the calling line engaged thereby, the back contact and armature of the line relay 100, which released when the calling subscriber replaced his receiver upon its switch hook, and the back contact and armature of relay 106 to ground. The operation of the relay 102 again establishes the operating circuit for relay 107 and a circuit is thereupon established for relay 112 extending from grounded battery through the left-hand winding of relay 111, winding of relay 112, the outer right-hand armature and back contact of relay 104, the front contact and right-hand armature of relay 107 and from thence over

the locking circuit of relay 102. The operation of relay 111 in the circuit above described, has no effect at this time. The energization of relay 112 opens the energizing circuit for relay 138 which supplied talking current to the called subscriber's line. The operation of relay 107 also establishes a self-interrupting circuit for the motor magnet 108 of the line finder, said circuit being traceable from grounded battery through the winding, armature and contact of magnet 108, the inner left-hand armature and front contact of relay 102, the left-hand armature and front contact of relay 107, brush 109 and from thence over the previously described circuit to the ground at the relay 110. The motor magnet 108 operates to step the brushes of the line finder B until the brush 116 encounters a terminal having no ground thereon. This might be the normal terminal of the brush or it might be a terminal of a line which may originate a call while the switch is returning to normal. In the latter event the line finder will stop upon the terminals individual to this calling line and the operation will be the same as previously described. When the brush 116 encounters an open terminal in the return of the switch towards its normal position, the locking circuit of relay 102 is opened thus permanently breaking the operating circuit of the motor magnet 108. The release of relay 102 also opens the circuit for relays 111 and 112 which thereupon release, thus completely restoring the apparatus of the line finder and selector switch to normal.

At the time of the release of relay 110 of the selector the ground, which was extended to the conductor 202 through the brush 123 to maintain the relay 200 of the connector switch energized, is removed and said relay 200 thereupon releases. The brush 222 of the connector E is thereupon grounded at the relay 200 and this ground is extended through the back contact and inner right-hand armature of relay 208 and the contact, armature and winding of stepping magnet 213 to grounded battery. This being a self-interrupting circuit, the motor magnet will operate to step the brushes of the connector until their normal terminals are reached, whereupon the circuit for said motor magnet will be permanently opened. The release of relay 200 also establishes an operating circuit for relay 208 extending through the right-hand winding thereof to the grounded brush 222. The operation of relay 208 extends the ground from the brush 222 through the inner right-hand armature and front contact of relay 208, the outer left-hand armature and back contact of relay 200 and the conductor 202 to the terminal individual to the connector over which the brush 123 of the selector passes.

The ground on this terminal is multiplied to other similar terminals and will prevent a selector from seizing the trunk extending to connector E while the latter switch is returning to normal.

A subscriber within the exchange may secure connection to the attendant's position by dialing 0. In response to the removal of the receiver from its switch hook at the calling substation, the line finder B will operate to engage the terminals of the calling line in the same manner as previously described and in response to ten impulses transmitted a selector C will operate as hereinbefore set forth to step its brushes to engage the first set of terminals in the selector bank which are assigned to the first trunk leading to the attendant's position. In the present showing, provision is made for two of such trunks and the terminals of these trunks over which brush 125 of the selector passes are indicated as 137. At the termination of the ten impulses transmitted brush 125 is in engagement with the first of the terminals 137 and a circuit is established for relay 138 extending from grounded battery through the left-hand winding of said relay, the back contact and inner right-hand armature of relay 135, the brush 125, the right-hand normal contacts of relay 128, which released at the termination of the impulses as previously described, and the right-hand armature and front contact of relay 110 to ground. Relay 138 operates and locks through its front contact and inner left-hand armature and from thence over the energizing circuit therefor. The energization of relay 138 establishes an operating circuit for relay 111 extending from grounded battery through the left-hand winding of relay 111, winding of relay 112, the outer right-hand armature and front contact of relay 104, the right-hand armature and front contact of relay 138, the back contact and inner left-hand armature of relay 135, the right-hand normal contacts of relay 130, and the right-hand armature and front contact of relay 110 to ground. Relay 111 locks through its outer left-hand armature and front contact, the outer left-hand armature and back contact of relay 128 and the left-hand armature and front contact of relay 110 to ground. The operation of relay 111 establishes, as previously described, energizing and locking circuits for relays 134 and 135.

If the first trunk extending to the attendant's position is busy, this condition is denoted by ground upon the test terminal which brush 123 engages. It will be recalled from the previous description of the operation of the selector circuit that at the time of testing, the relay 129 is energized through its right-hand winding. With ground upon the brush 123, a circuit is es-

tailed to maintain relay 129 energized and to cause the operation of relay 133, said circuit being traceable from grounded battery through the left-hand winding of relay 129, the left-hand normal contact of relay 130, the right-hand winding of relay 133, the front contact and inner right-hand armature of relay 129 to ground at the brush 123. It is noted that the energizing circuit for the relay 111 extends through the winding of relay 112 but if the trunk is busy and relay 133 energizes as described, relay 112 is prevented from operating due to the short circuit established from ground through the left-hand armature and front contact of relay 110, back contact and outer left-hand armature of relay 128, the front contact and outer left-hand armature of relay 111 and the outer left-hand armature 15 and front contact of relay 133. The operation of relay 133 also establishes the self-interrupting circuit for motor magnet 131 extending to ground at the front contact and outer left-hand armature of relay 135 and the switch therefor advances to engage the terminals of the next trunk. This operation continues until the brush 123 finds a terminal free from ground. If all of the trunks to the attendant are busy all of the 20 terminals associated with the brush 125 of the selector following those assigned to the attendant's trunks are connected to relays 129 and 133 due to the operation of either of the relays 111 or 134. the lamp 305 will light. The operator releases the connection by restoring either key 303 or 304 and the removal of ground from the terminal engaged by brush 123 and the 5 restoration of the receiver at the calling substation causes the release of the selector switch as previously described.

The attendant may originate a local call to any substation within the private branch 10 exchange by operating key 307 which connects her head set in circuit with the line relay 308 through contacts of the cut-off relay 309. In the same manner as hereinbefore described, an idle line finder similar 15 to the finder B is caused to hunt for the terminals individual to the attendant's position after which the attendant may complete the connection in the same manner that a call is established between subscribers.

20 A subscriber within the private branch exchange may secure a direct connection to the central office by dialing the digit 2. Upon the initiation of the call the line finder B operates in the same manner as before 25 described and associates a selector C with the calling line so that in response to the two impulses transmitted, the brushes of the selector will take one step to engage the brush 125 with the second terminal in its 30 row. Upon the release of the relay 128 and consequent grounding of the brush 125, an energizing circuit is established for the relay 111 through the right-hand winding thereof. Relay 111 locks up in series with 35 relay 112 as before described but if relay 133 is operated due to the engagement of the brush 123 with a terminal of a busy trunk, relay 112 is short-circuited. The operation of relay 111 also causes the energization of relays 134 and 135 as previously 40 described. The test for an idle trunk is made in the same manner as hereinbefore set forth and if none of the trunks leading to the central office are idle, the switch will

45 continue to step until the last terminals of the bank are reached whereupon the calling subscriber is given a busy tone. The replacing of the receiver upon its switchhook at the calling substation will then release 50 the switches in the same manner as previously described.

If an idle trunk is found, no ground being 55 on the test terminal thereof, relay 133 will fail to operate, thus stopping the switch on the terminals of the idle trunk. Relay 112 will energize to open the circuit for relay 113 and connect the calling line direct to the trunk and around the condensers 142.

It will first be assumed that all of the 60 trunks leading from the private branch exchange terminate in a manual central office F conventionally illustrated at the right of Figure 4. Upon the operation of relay 112, the subscriber's line is extended through normal contacts of relay 400 in the central office

trunk circuit and the windings of line relay 401. This latter relay energizes to establish an obvious energizing circuit for slow-to-release relay 402 which, in closing its left-hand armature and front contact, extends 70 busy ground from the left-hand normal contacts of slow-to-release relay 403 to the test terminal engaged by brush 123 of the selector to cause the multiple terminals of the trunk to test busy to all 75 other switches C. The busy lamp 404 is lighted by the energization of relay 402 over an obvious circuit to indicate to the attendant that a particular trunk has been taken for use. The energization of relay 401 80 grounds the tip side of the trunk extending to the central office F through the right-hand armature and front contact of relay 401 and innermost right-hand armature and back contact of relay 405. This ground, in 85 the present instance, is shown as extending from the back contact and left-hand armature of relay 600 but, inasmuch as the apparatus including the code switch shown in Figure 6 is not employed where the trunks 90 of the private branch exchange extend to a manual central office, it will be understood that this ground may be directly connected to the right-hand armature of relay 401. The operation of relay 401 also establishes 95 a circuit for relay 406 extending from grounded battery through the winding of relay 406, the upper contacts of release key 407, the normal contacts of the dialing key 408, left-hand normal contact of relay 406 100 and front contact and left-hand armature of relay 401 to ground. Relay 406 energizes and locks in a circuit through its front contact and inner left-hand armature to ground at the right-hand armature and front contact of relay 402.

The grounding of the tip side of the trunk by the operation of relay 401 causes the energization of line relay 408' at the central office F whereupon the usual line lamp at 110 said office individual to the seized trunk is lighted. The operator then answers the call by inserting a plug into the jack of the trunk in the usual manner. This operation closes a circuit extending from grounded battery 115 in the cord circuit employed by the operator, through the right-hand normal contacts of the flashing or disconnect key 409 which may be used for recalling the central office operator or giving a disconnect signal, the 120 right-hand armature and normal contacts of relay 410, the winding of line relay 411, the upper normal contacts of key 412 and the left-hand normal contacts of key 409 to ground in the operator's cord circuit. Relay 411 energizes in this circuit and establishes an obvious operating circuit for relay 403 which, in attracting its left-hand armature, disconnects the ground potential from the left-hand ar- 125 130

mature and front contact of relay 402 and extends it directly through the left-hand armature of relay 403 to the brush 123 and lamp 404.

- 5 Relays 403 and 406 now being energized, a circuit is established for relay 400 extending from grounded battery through the winding of said relay, the lower normal contact of key 412, conductors 413 and 414 70 which are strapped together when the trunks lead to a manual office, the front contact and inner left-hand armature of relay 406 and the right-hand armature and front contact of relay 403 to ground. Relay 400 energizes 75 to extend the calling line over the trunk to the central office through the winding of supervisory relay 415 which is bridged across the trunk. Conversation may now proceed between the calling subscriber and the central office operator. The operation of relay 400 causes the release of relay 401 but relay 402 remains operated due to ground at the front contact and outer left-hand armature of relay 400. The operation of the supervisory relay 415 establishes an obvious 80 energizing circuit for relay 410 which upon operating, opens the energizing circuit of relay 411 which then releases. Relay 410 also bridges the non-inductive shunt 416 around the active winding of the supervisory relay 415. 85

At the termination of the conversation, the restoration of the receiver upon its switch hook at the calling substation releases the supervisory relay 415 whereupon relay 410 deenergizes. Relay 411 is then operated over its previously described circuit thus preventing the release of relay 403. As a winding of relay 411 is of a high resistance, the supervisory relay at the central office is released thus giving the operator thereat the disconnect signal in the usual manner. When the operator removes the plug from the jack, relay 411 releases and causes, in turn, the release of relays 403, 400, 402 and 406 and the extinguishment of the busy lamp 404. The trunk circuit is now restored to normal and the removal of ground from the brush 123 causes the release of relay 404 which effects the return to normal of the switches B and C in the same manner as previously described. 100

Should the central office operator disconnect before the calling subscriber replaces his receiver upon its switchhook, relays 415 and 410 will release but line relay 411 will fail to operate. This permits the release of relays 403 and 400. The release of the latter relay again causes the energization of relay 401 to prevent the release of relays 402 and 406 and to again connect ground to the tip side of the trunk leading to the central office whereupon the line lamp thereat will again be lighted. 105

65 In case a subscriber is denied direct connection to the central office, the inner right-hand armature of the cutoff relay 101 of the subscriber's line is connected by a conductor 139 to the terminal in the line finder bank individual to said line over which brush 140 70 passes. When the cut-off relay 101 is operated by the finding of the calling line and the impulses have been transmitted to operate selector C, a circuit is established extending from grounded battery through the inner armature and front contact of relay 101, conductor 139, the brush 140, the left-hand winding of relay 141, the brush 125, the right-hand normal contacts of relay 128, the right-hand armature and front contact of relay 110 to ground. Relay 141 energizes and locks through its right-hand winding, front contact and inner right-hand armature, the outer left-hand armature and back contact of relay 128 and the left-hand armature and front contact of relay 110 to ground. The operation of relay 141 connects the terminals individual to the central office trunks over which brush 125 passes to the right and left-hand windings respectively, of relays 129 and 133 through the front contact and outer right-hand armature of said relay 141. Relays 129 and 133 therefore remain operated and the selector switch C continues to step over the terminals of the central office trunk even though these trunk are idle. The brushes of the switch C are also stepped over the other terminals in the same manner as previously described and upon reaching the last vertical row of terminals, 100 which is the all-busy position, the brush 123 encounters ground which extends from the right-hand armature and front contact of relay 110, the right-hand normal contacts of relay 130 and the inner left-hand armature and front contact of relay 141. Relays 129 and 131 are thereby maintained energized and the brushes of the selector C therefore do not stop upon the last row of terminals but continue on to their normal positions. 110

The attendant at substation 306 may call the central office F by operating the listening key 417 which extends ground from the right-hand normal contacts of relay 403 115 through an alternate contact of key 417, and the right-hand normal contacts of relay 421 to the tip side of the trunk with the result that line relay 408' at the central office will operate to light the line lamp thereat. The closure of the lowermost alternate contact of key 417 extends ground through the middle normal contacts of key 409 and from thence in parallel through the guard lamp 420 and the winding of relay 405 to grounded battery. The lamp 420 is lighted and the energization of relay 405 extends the last mentioned ground through its front contact and outer right-hand armature and the right-hand normal contacts of relay 418 to 125 130

the multiple test terminals appearing in the banks of selector switches C whereby the trunk will test busy to these switches. The lamp 404 is also lighted by the above mentioned ground to indicate the busy condition of the trunk. The central office operator, observing the lighted condition of the line lamp individual to the trunk, answers the call by inserting a plug into the jack of said trunk whereupon the supervisory relay 415 is energized. The operation of this relay causes the energization of relay 410 which, in closing its right-hand front contact, includes the non-inductive winding 416 of the supervisory relay in the circuit for talking purposes. The energization of relay 415 also closes an obvious circuit for relay 403 which, when energized, disconnects ground from the tip side of the trunk.

The attendant may release the central office trunk by operating the disconnect key 409 and by restoring listening key 417 which removes ground at key 417 from the multiple test terminals and causes the release of relay 405 and the extinguishment of lamp 420. The replacing of the receiver upon its switch hook at the attendant's substation 206 opens the circuit to supervisory relay 415 which thereupon releases to cause the deenergization of relay 410 and the consequent release of relay 403. The lamp 404 is extinguished and ground removed from the test terminals of the trunk upon the release of relay 403. The central office operator upon receiving the disconnect signal in the usual manner removes the plug from the jack.

For an incoming call from the manual central office D to the attendant at substation 306, the operator at the central office inserts the plug of the cord circuit in the jack and thereby energizes the relay 411 over the previously described circuit therefor, whereupon the relay 403 operates to ground the multiple test terminals of the trunk, and the busy lamp 404 is lighted. When a central office operator applies ringing current to the line, said current extends from the ring side of the trunk through the outer right-hand armature and back contact of relay 406, the left-hand winding of relay 422 and the upper normal contact of key 412 to the tip side of the trunk. Relay 422 energizes and locks through its right-hand winding, front contact and armature, the back contact and outermost armature of relay 405, and the right-hand normal contacts of relay 418 to ground at the left-hand armature of relay 403. A circuit for lighting the line lamp 423 is also established which extends through the left-hand armature and front contact of relay 422 and from thence over the locking circuit of said relay. The attendant at substation 206, observing that a call is awaiting attention, first operates the listening key 417 which energizes relay 405 and lights the guard lamp 420 as previously described. The energization of relay 405 opens the locking circuit of relay 422 and extinguishes the lamp 423. The energization of relay 405 also bridges the upper and lower windings of the retardation coil 424 across the trunk through the high resistance winding of relay 411 to hold said trunk, the middle winding of said coil being normally shunted through the outer left-hand armature of relay 410. The attendant now removes the receiver from its switch hook at her substation whereupon the supervisory relay 415 operates in series in the central office operator's telephone set. The operation of relay 415 again operates relay 410 to close the talking circuit and open the shunt around the middle winding of the retardation coil 424. Relay 411 releases to remove the coil 424 from the line and opens the original energizing circuit for relay 403 but this relay is maintained energized by ground at the left-hand armature and contact of relay 415.

The attendant may now converse with the central office operator and if the call is to be extended to a subscriber within the exchange, the attendant leaves the listening key 417 operated and actuates the dialing key 408. Relay 406, the circuit of which extends through the lower contacts of relay 408, will not energize.

Upon the operation of relays 421 and 402, following the actuation of the listening key 417 and energization of relay 401, a circuit is established for stepping relay 500 of the selector switch shown in Figure 5, which circuit is traceable from grounded battery through the left-hand winding of said relay, the brush 501 in its normal position, the right-hand normal contacts of relay 502, the front contact and inner left-hand armature of relay 421 and the right-hand armature and contact of relay 402 to ground. Relay 500, however, does not operate due to a short-circuit extending from ground on the right-hand armature and front contact of relay 401, the innermost armature and front contact of relay 405 which is operated by the actuation of key 417, the no-test key 440 and the outer right-hand armature and back contact of relay 503. The selector switch is now ready to receive impulses from the attendant's position and since relay 401 is now under the control of the attendant's telephone set, said relay will respond to the impulses transmitted. The opening of the contact and right-hand armature of relay 401 in response to the first impulse removes the short circuit from the left-hand winding of relay 500 whereupon this relay operates to close an obvious circuit for slow-to-release relay 505. The latter relay establishes an energizing circuit for re-

lay 503 extending from grounded battery through the right-hand winding of said relay, the front contact and left-hand armature of relay 505, the lower contacts of key 407 and the left-hand armature and front contact of relay 403 to ground. Relay 505 also establishes, through its right-hand armature, an energizing circuit for relay 502 but the winding of this relay is short-circuited through its back contact and left-hand armature to ground at the left-hand armature of relay 500. When the latter relay releases at the termination of the first impulse, the short circuit for relay 502 is removed and this relay operates to place the motor magnet 506 under the control of the relay 500. It will thus be apparent, as in the case of the selector C, that the first impulse transmitted to the selector of Figure 5 is absorbed by the action of relay 502 for the same purpose as previously described. In response to the subsequent impulses relay 500 operates to close a stepping circuit for magnet 506 which advances the switch to a trunk leading to a connector switch such as shown in Figure 2. During the transmission of the impulses, relay 505 remains operated but at the end of a series of impulses said relay releases after an interval and connects the right-hand windings of relays 503 and 507 in series through the inner right-hand armature and back contact of relay 503 to the brush 508. The release of relay 505 also causes the deenergization of relay 502 which, in releasing, extends ground from the right-hand armature of relay 402 to the brush 501.

If the wanted subscriber's line is in the groups served by the first group of connectors, the brushes of the selector switch will be stepped until the brush 501 engages the terminal 509, certain of the terminals of the selector bank being omitted as in Figure 1. Ground on the brush 501 will thereupon operate relay 510 and this relay will lock through its front contact and right-hand armature to ground, at the left-hand armature of relay 403. The operation of relay 510 connects the terminals of the second group of connectors, such as terminals 511, to the left-hand windings of relays 503 and 507 in parallel. The selector will hunt for an idle trunk leading to a connector switch in the same manner as previously described in connection with switch C and if the first trunk encountered is busy the terminal engaged by brush 508 will be grounded to maintain relay 503 energized and to operate relay 507. The operation of relay 507 extends ground from the armature and contact thereof through the back contact of relay 500 to the back armature and winding of the motor magnet 506 to cause the latter to step the brushes of the switch to the terminals of the next trunk. This operation

continues until an idle trunk is found but if all trunks leading to the first group of connectors are busy, the switch will continue to step over all of the terminals until the last terminals are reached whereupon the switch will be brought to rest in the same manner as described in connection with switch C. A busy tone from the apparatus 512 will then be transmitted to the attendant's telephone set.

As shown in Figure 5, the trunk leading to the connector of Figure 2 is connected to terminals assigned to the second group of connectors so that it will be necessary for the attendant to send sufficient impulses to step the brushes of the selector until brush 501 is brought in engagement with the first of the terminals 511. In this instance, relay 510 will not operate and when brush 501 is grounded, as previously described, this ground will be extended to all of the terminals assigned to the first group of connectors through the back contact and left-hand armature of relay 510 to maintain relay 503 and 507 operated during the trunk hunting operation of the switch. The test for an idle trunk leading to a connector in the second group therefore takes place in the same manner as described in connection with the first group of connectors and upon encountering an idle trunk such as the one shown, relays 503 and 507 release when ground is not present upon the terminal engaged by brush 508. The release of relay 503 extends the trunk leading from the attendant's position through to the brushes 513 and 514; supplies ground to the brush 508 from the left-hand armature and front contact of relay 403; and connects ground to the brush 515 from the right-hand armature and front contact of relay 401 through the innermost right-hand armature and front contact of relay 405 and the no test key 440. These two grounds are connected to the conductors 202 and 206 of the connector circuit and perform the same functions as the ground supplied to these conductors from the switch C.

After the connector has been seized it is operated under the control of relay 401 to select the desired line. The connector functions in the same manner as described in connection with a local call and if the line is found to be idle the bell at the substation is rung and a portion of the ringing current is transmitted back to the attendant's telephone set in the same manner as described with respect to the call initiated at the substation A. Upon hearing this ringing current the attendant restores the listening and dialing keys 417 and 408 and thereby causes the release of relays 421, 401 and 402. Relay 405, however, remains locked up to ground at the left-hand armature and front contact of relay 403 and the central office supervisory

relay is maintained operated through the low resistance winding of relay 411 and windings of the retardation coil 424. At the time the listening key 417 was operated and relay 405 energized, a circuit for guard lamp 420 was also established in parallel with relay 405 and said lamp remains lighted during the selection of the called line by the attendant and the ringing of said line to indicate to the attendant that the subscriber has not answered. When the called subscriber removes his receiver from its switch hook his substation apparatus is connected through brushes 513 and 514 and normal contacts of relays 503 and 400 to the winding of relay 401 which relay thereupon operates and causes the energization of relays 402 and 406, the circuit for the latter relay being now closed at the dialing key 408. Relay 406 locks up in the same manner as previously described. As relay 403 is already operated and the conductors 413 and 414 are connected together either permanently as previously referred to or by means of a relay in the code circuit of Figure 6, relay 400 operates in the same manner as previously described and connects the called subscriber's substation through front contacts of the relay 400 to the central office trunks. The operation of the relay 400 releases relay 401 but relay 402 is maintained energized by ground at the outer left-hand armature and front contact of relay 400. Relays 415 and 410 now operate and in so doing the latter relay removes the short-circuit from the middle winding of retardation coil 424 and places the non-inductive shunt 416 across the winding of the relay 415. The operation of relay 410 also establishes a circuit for relay 418 extending from grounded battery through the right-hand winding of said relay, the left-hand armature and front contact of relay 405, the front contact and outer left-hand armature of relay 406 and the front contact and inner left-hand armature of relay 410 to ground. Relay 418 locks up through its left-hand winding, front contact and inner left-hand armature, the lower normal contacts of key 407 and left-hand armature and front contact of relay 402 to ground. The operation of relay 418 places the locking circuit of relay 405, which extended through the front contact and outermost armature of said relay, under the control of relay 410. The operation of relay 418 also causes the energization of relay 427 over a circuit extending from grounded battery through the winding of said relay, the front contact and inner right-hand armature of relay 418 and from thence over the energizing circuit for the latter relay to ground at the front contact and inner left-hand armature of relay 410. The operation of relay 427 opens the

circuit for lamp 420 which is thereupon extinguished.

It is to be noted that when the attendant operates the listening key 417 in response to a call from the central office, the closure of the next to the lowermost contact and associated spring of said key grounds the conductor 431 so that in cases where the code switch of Figure 6 is employed, relay 614 of said switch will be operated through its left-hand winding. The operation of this relay connects the conductors 413 and 414 to prevent the code switch from responding to the impulses transmitted from the attendant's position, in a manner which will hereinafter appear.

After the connection has been established from the central office to the called subscriber, if the latter desires to recall the attendant he may do so by depressing his switchhook momentarily or by operating the dial. This causes the momentary release of relays 415 and 410 whereupon relay 405 releases. Relay 427 being slow to release, maintains its armature attracted during the interruptions in the line circuit which cause the release of relay 410 and thereby prevents the opening of the holding bridge across the line through the retardation coil 424. When relay 410 again operates, a circuit is established for the line lamp 423 extending from grounded battery through said lamp, the left hand armature and back contact of relay 422, the outer left hand armature and front contact of relay 418, the outermost right hand armature and back contact of relay 405, the front contact and outer right hand armature of relay 418, the front contact and left hand armature of relay 406 and the inner left hand armature and front contact of relay 410 to ground. In answer to the lighting of the lamp 423, the attendant operates the listening key 417 which again operates relay 405 thereby opening the circuit for lamp 423 and extinguishing the same.

If the attendant has occasion for any reason to transfer a call to another line than the one originally selected, she may do so by operating the key 407. This opens the circuit for relays 406 and 418 permitting these relays to release provided they have been operated by the called subscriber answering the call. The operation of release key also grounds the off normal brush 516 through the lower alternate contact of key 407 and the left hand armature and front contact of relay 403. The ground on brush 516 causes the operation of relays 503 and 507 through their left hand windings in parallel and the operation of the latter relay establishes a self-interrupting circuit for the motor magnet 506, which will thereupon operate to return the brushes of the switch to their nor-

mal positions where the circuit for relays 503 and 507 is opened and these relays thereupon release. The attendant will then proceed to establish another connection to a called subscriber in the same manner as previously described.

The attendant may, if it is found necessary, secure a connection to a busy called line without awaiting the termination of a conversation on such line. It will be recalled in the description of the connector switch shown in Figure 2 that when the connection is established to the called substation D an energizing circuit for relay 216 is established but this relay is short circuited by ground on the conductor 206 extending from the terminal of selector C engaged by brush 124. On an incoming call from the central office, conductor 206 is also supplied with ground from the front contact and right hand armature of relay 403, the inner right hand armature and back contact of relay 406, the normal contact of key 408, the no-test key 440, the outer right hand armature and back contact of relay 503, and the brush 515. This ground short circuits relay 216 of the connector taken for use. Finding the wanted line busy, the attendant operates key 440 which removes the short circuit from the winding of relay 216 and this relay thereupon operates. It will be understood that the operation of relay 216 depends upon the energized condition of relay 215 which remains energized when the connector taken by the attendant stops on a busy line. The left hand armatures and front contacts of relay 216 now extend the trunk through the condensers 223 and 224 to the brushes 211 and 212. The operation of relay 216 transfers the holding circuit for relays 208 and 215, which extended through the right hand normal contacts of relay 216 to ground at the front contact and outer right hand armature of relay 200, to the front contact and right hand armature of relay 216, the inner left hand armature and front contact of relay 200, the front contact and outer right hand armature of relay 208 to the brush 207 which is grounded by the busy condition of the called line. At the termination of the conversation between the original subscribers, the ground at brush 207 is removed, thus releasing relays 208 and 215 which, in turn, release relay 216. The connection to the subscriber's line from the central office through the connector employed by the attendant is then completed in the same manner as previously set forth in describing the operation of a call between subscribers.

In the event that the attendant extends an incoming call to a subscriber's substation and she finds the line busy and does not wish to hold a connector on the ter-

minals of the called line, it is necessary that the trunk be released. This is done by operating the key 409 after restoring the listening key 417 to normal. The operation of key 409 opens the circuit for relay 403 which thereupon releases and removes the holding bridge from the trunk. The key 409 may also be used for flashing the operator at the manual office F or a special position of a machine switching office. This is accomplished by operating the key 409 with listening key 417 in its operated position. The trunk to the central office is thereby opened but the supervisory relay 415 is maintained energized in series with the attendant's telephone circuit by means of ground supplied from battery through resistances connected to the inner contact springs of said key 409. Thus the relay 403 is maintained in its energized condition and the trunk will not be released.

On an incoming call from central office to a subscriber within the exchange, the replacing of the receiver upon its switchhook at the called subscriber's substation causes the release of relays 415 and 410. Relay 405 thereupon releases due to the removal of ground from the inner left hand armature and front contact of relay 410. Relay 427 also releases after an interval and the bridge through the retardation coil 427 is thereupon opened at the right hand armature and front contact of relay 427 to permit the supervisory relay at the central office to release. The central office operator noting the signal lighted by the release of the supervisory relay removes the plug from the jack and thus causes the release of relay 411. The restoration of the latter relay opens the circuit for relay 403 which thereupon releases to open the energizing circuit for relay 421. When relay 421 returns to normal relay 401 does not operate inasmuch as the called subscriber has replaced his receiver upon its switchhook. Therefore relay 402 releases to open the locking circuits for relays 406 and 418 which thereupon restore. The release of relays 402 and 403 extends ground from the left hand normal contacts of the latter relay through the left hand armature and back contact of relay 402 to the brush 516 whereupon relays 503 and 507 are operated as before described to cause the restoration of the connector switch to normal. The connector switch which was employed to extend the central office trunk to the called subscriber is returned to normal in the same manner as described in connection with the local call and apparatus employed in establishing the connection is then ready for another call.

In establishing a call to a machine switching office the attendant must, after the trunk

leading to said office has been taken for use, operate the key 412 in order to transmit impulses to the central office to operate switches thereat which may be of any desired construction and which do not form a part of the present invention. The operation of key 412 opens the bridges through the left hand winding of relay 422 and windings of the retardation coil 424 and 10 places a non-inductive shunt across the winding of relay 415 thus leaving the attendant a clear line to the central office for dialing purposes. When the attendant has originated a call to the central office she 15 may extend it to a station within the private branch exchange in the same manner as described in connection with an incoming call.

The extension of a calling subscriber's 20 line to a central office trunk when said trunks terminate in a machine switching office will now be described. Under this condition, the attendant at the private branch exchange has supervision over certain calls 25 by the subscribers which are extended to the machine switch central office. For this purpose, there is provided a code circuit including a switch, shown in Fig. 6, which is responsive to impulses transmitted from 30 the calling subscriber's substation to said office to cause a signal to be operated before the attendant to notify her that a call on one of the central office trunks is awaiting supervision. If the call is one that does 35 not require the attendant's supervision, other conditions take place in the code circuit which prevents the signal being operated before the attendant. In this instance, the impulses are simply repeated to the 40 central office to operate the switches thereat whereby the call is extended to the desired station.

When the subscriber within the private branch exchange proceeds to establish a central office call to the machine switching office, 45 the switches B and C respond as previously described to connect the subscriber's line to an idle central office trunk. Relays 401, 402 and 406 then operate as previously described. 50 The operation of relay 401 extends ground at the back contact and left hand armature of relay 600 to the tip side of the trunk leading to the central office, whereupon a selector switch will operate to engage the terminals 55 of the selected trunk, and a circuit is then established which extends through the windings of the line relay 411 in the trunk circuit, which relay, in energizing, operates relay 403. Upon the closure of the right- 60 hand alternate contact of the latter relay, conductor 414 is grounded through the inner right hand armature and front contact of relay 406. At the same time ground at the right-hand alternate contact of relay 403 is 65 extended to conductor 429. The grounding

of conductor 414 establishes an energizing circuit over conductor 444 for slow-to-release relay 600 extending through the back contact and outer left hand armature of relay 614. Relay 600 in closing its left 70 hand armature and front contact bridges the right-hand armature and contact of line relay 401 so that when this relay vibrates its armatures in response to the transmission of impulses from the calling substation, the 75 impulses will be repeated through this bridge to the central office to operate the switches thereat. The energization of relay 600 also establishes a circuit for the stepping relay 602 extending from grounded 80 battery through resistance 601, the right-hand armature and front contact of relay 600 and the right-hand winding of relay 602 to ground. This winding of relay 602 is short circuited by ground extending from 85 the left-hand armature and contact of relay 401 over conductor 428 so that relay 602 will not operate upon the energization of relay 600.

When the calling subscriber transmits the 90 first series of impulses corresponding to the first digit of the called number, the circuit of relay 401 is interrupted so that impulses will be repeated to the central office and the short circuit removed from the right-hand 95 winding of relay 602. This latter relay, therefore, responds to each removal of the short circuit by attracting its armatures. The closure of the right-hand armature and contacts of relay 602 establishes circuits for 100 slow-to-release relay 603 and motor magnet 604, the circuit for the latter being through the resistance 605. In energizing, relay 602 locks up through the armature and contact of relay 604 and remains in this condition 105 until the contact and armature of motor magnet 604 is opened which occurs at the end of the stroke. Normally, the ground extending from the right-hand alternate contact of relay 403 over the conductor 429 110 is applied to brush 607 of the code switch through the left-hand normal contacts of relay 603 and the inner right-hand armature and back contact of relay 612, and brush 606 is grounded from the normal contacts 115 of relay 603. When the latter relay energizes ground on conductor 429 is extended through the left-hand armature and front contact of said relay through conductor 617, branches of which are associated with the 120 rows of contacts over which brushes 608 and 609 pass.

When employing the code circuit and it is desired that the attendant have supervision over certain calls, the contacts of the 125 code switch bank over which brushes 608 and 609 pass and which correspond to certain digits of such calls are connected to the conductor 617, otherwise these contacts are not so connected. The contacts or terminals 130

associated with each of the brushes 608 and 611 inclusive, are divided into two groups, separated by a vertical intermediate row of contacts including contact 620. Only a few 5 of the terminals of each of the groups is shown in Fig. 6, the remaining terminals of the groups being omitted for simplicity and economy of space.

In response to the series of impulses corresponding to the first digit dialed, the code 10 switch is stepped to engage the brush 608 with a terminal in the first group of contacts associated therewith. If the contact then engaged by said brush is connected to conductor 617, relay 612 will be energized over a circuit extending from grounded battery, through the winding of said relay, the right-hand armature and back contact of relay 615, brush 608 and the contact engaged 15 thereby, conductor 617, and from thence to ground on the conductor 429 through the left-hand armature and front contact of relay 603, this circuit being established before relay 603 releases at the termination 20 of the series of impulses. When relay 603 releases, a locking circuit for relay 612 is established from grounded battery, through the winding, front contact and inner right-hand armature of said relay, and the normal 25 contact of relay 603 to ground on conductor 429. Brush 606 is now engaged with the connected terminals 621 and when relay 603 releases, ground is extended through its right-hand normal contacts, brush 606, terminals 621, winding of relay 613 to grounded 30 battery, this relay being adjusted for slow operation and release. The closure of the front contact of relay 613 establishes a self-interrupting circuit for motor magnet 604 35 extending from grounded battery, through the resistance 605, winding, contact and armature of magnet 604, left-hand armature and back contact of relay 602, front contact and armature of relay 613 and from thence 40 to ground at a contact of relay 603. The motor magnet then operates to step the switch until the brush 606 engages contact 620, whereupon the operating circuit for 45 said motor magnet will be opened and the 50 switch will come to rest.

The second series of impulses is now 55 transmitted and relay 603 again operates in response to the first energization of relay 602 to open the locking circuit for relay 612 which then releases. Motor magnet 604 is 60 operated in response to the energization of stepping relay 602 and the brushes of the switch are then stepped over the contacts of the second group. Brush 606 is now in engagement with the connected terminals 622 and brush 608 with a contact in the second 65 group associated therewith. If this latter contact is connected to the left-hand armature and front contact of relay 603 through conductor 617, relay 612 again operates and

locks up in the same manner as previously described and relay 613 again operates to close the previously mentioned self-interrupting circuit for motor magnet 604 whereupon the switch is stepped to its normal 70 position. Upon reaching this position, ground is extended from the right-hand normal contacts of relay 603 through the brush 606 and its normal contact, the inner left-hand armature and front contact of relay 612, the back contact and outer right-hand armature of relay 614, and the winding of relay 615 to grounded battery. The latter relay energizes in this circuit and locks up through its front contact and inner left-hand winding and the inner right-hand 75 contacts of relay 614 to ground on the conductor 429. The energization of relay 615 transfers the operating circuit for relay 612 from brush 608 to the brush 609 through 80 the right-hand armature and front contact of relay 615.

The series of impulses corresponding to the third digit of the called number is now 85 transmitted and the code switch again operates to engage its brushes with the associated contacts of the first group. With relay 615 energized and locked up, should brush 609 engage a contact in the first group connected to the conductor 617, relay 612 90 will then energize through the right-hand armature and front contact of relay 615 and will lock up when relay 603 releases at the termination of the series of impulses. With brush 606, in engagement with terminals 95 621, relay 613 operates as before to cause motor magnet 604 to step the brushes of the switch to the intermediate vertical row of contacts including contact 620.

The fourth digit of the desired number is 100 now dialed to again step the brushes of the code switch over the second group of the associated contacts. The contacts of the second group over which brush 609 passes 105 and which correspond to certain digits of numbers requiring supervision are connected to the conductor 617. Such contacts as just mentioned in the second group associated with brush 611 are connected to conductor 619 which extends to the right-hand winding of relay 614. Therefore, should brushes 110 609 and 611 engage such contacts as mentioned above, when the switch is brought to rest at the termination of the fourth set of impulses, relay 612 again energizes and locks 115 up and upon the release of relay 603, relay 613 again energizes. This relay being slow to operate, a circuit is closed before said relay can open its back contact, which circuit extends from ground, through the 120 right-hand normal contacts of relay 603, brush 606, a terminal 622, the armature and back contact of relay 613, the outer right-hand armature and front contact of relay 125 612, the outer left-hand armature and front 130

contact of relay 615, brush 611 and the contact engaged thereby, conductor 619, and the right-hand winding of relay 614 to grounded battery. Relay 614 energizes in this circuit and locks up through its right-hand winding, inner right-hand armature and front contact to ground at the conductor 429. The energization of relay 614 opens the energizing circuit for relay 600 and the locking circuit for relay 615 and these relays thereupon release. Relay 612 being still energized and locked up, ground on conductor 429 is extended through the left-hand armature of relay 603, which releases at the termination of the series of impulses, through the inner right-hand armature and front contact of relay 612, front contact and inner left-hand armature of relay 614, conductor 430, back contact and outer left-hand armature of relay 418, back contact and left-hand armature of relay 422 and the line lamp 423 to grounded battery. The line lamp is lighted in this circuit to inform the attendant that a call requires supervision.

When relay 613 energized upon the release of relay 603, motor magnet 604 is again operated to return the switch to its normal position. The energization of relay 614 connects conductors 413 and 414 through the outer left-hand armature and front contact of said relay and a circuit is thereby established for relay 400 extending from grounded battery, through the winding of said relay, the lower normal contact of key 412, conductor 413, front contact and outer left-hand armature of relay 614, conductor 444, 414, front contact and inner right-hand armature of relay 406, and the right-hand armature and front contact of relay 403 to ground. The energization of relay 400 extends the calling line over the trunk to the central office. The release of relay 600, upon the energization of relay 614, opens the bridge through which the impulses were repeated to the central office and again grounds conductor 425, but the relay 600, being slow to release, holds this bridge closed until the line is extended by the operation of relay 400.

If, at any stage in the selection of a called line, the code switch steps its brushes 608 and 609 into engagement with contacts not connected to conductor 617, and, provided relay 615 is operated, relay 612 will not energize and the release of relay 603 at the termination of the series of impulses, grounds the brush 607 through the inner right-hand armature and back contact of relay 612 with the result that this ground is extended over conductor 619 to grounded battery through the right-hand winding of relay 614. The latter relay energizes with the same result as previously described and prevents any further operation of the code circuit. The line lamp 423 is not lighted at this time due to the released condition of relay 612. Under the circumstances just referred to, if the contact not connected to conductor 617 is located in the first group, the switch will again operate as before upon the energization of relay 614 to step brush 606 into engagement with the terminal 620. Inasmuch as relay 612 is not operated, relay 613 will continue to remain energized through the back contact and outer left-hand armature of relay 612, contact 620 and the brush 606 to ground at the right-hand normal contacts of relay 603 and motor magnet 604 will therefore continue to step the brushes of the switch to their normal positions.

When relay 400 energizes to extend the calling line through to the central office, the supervisory relay 415 is included in the line circuit and is energized to close the energizing circuit for relay 410 which disconnects line relay 411 from the line circuit to cause the release of the latter relay. Relay 403 is now held energized under the control of the supervisory relay 415. The circuit for relay 401 is permanently opened upon the energization of relay 400 but relay 402 continues to remain energized under the control of relay 400.

When the attendant operates listening key 417, in response to the lighting of the line lamp 423, relay 405 energizes and causes the energization of relay 418 over a circuit previously described therefor. Relay 418 locks up and closes the energizing circuit for relay 427 to open the energizing circuit of the guard lamp 420. The energization of relay 418 opens the energizing circuit for the line lamp 423 which is then extinguished. The closure of the next to the lowermost contact of listening key 417 also extends ground through the left-hand winding of relay 614, over conductor 431 to provide an additional holding circuit for this relay.

When the trunk is released at the end of the call, restoration occurs as before and the release of relay 403 opens the locking circuits for relays 612 and 614, the former relay having remained energized after the last series of impulses which were transmitted in extending the call. With the release of relays 612 and 614, the code circuit is then in its normal position and ready to be operated upon the extension of another call to the central office.

To arrange the circuit to respond to three instead of four digit numbers, the necessary contacts of the first group associated with brush 611 are connected to conductor 619 so that relay 614 will operate through the front contacts and armatures of relays 615 and 612 before relay 613 has time to open its

back contact. The switch then stops with the brushes in engagement with the intermediate vertical row of contacts and remains in this position until the trunk is released and relay 403 deenergized, whereupon the locking circuit for relay 612 will be opened and this relay releases. Relay 613 is then operated through the back contact and outer left-hand armature of relay 10 612 with the result that the switch is stepped to normal as before.

When arranged to operate in conjunction with numbers containing both two and three digits, relay 616 is provided and is adapted 15 to be connected, through brush 610, to contacts in the first group corresponding to the first digit of two digit numbers to which the circuit is to respond. Therefore, upon the transmission of the impulses for the first 20 digit, relay 612 operates through brush 608 and the contact engaged thereby which is connected to conductor 617. Relay 612 locks up as before and upon the release of relay 603, a circuit is momentarily closed before 25 relay 613 can energize and open its back contact, said circuit extending from grounded battery, through the winding of relay 616, brush 610 and contact engaged thereby which corresponds to the contact 30 from the first group associated with brush 608, conductor 618, back contact and armature of relay 613, a terminal 621, brush 606, and the right-hand normal contacts of relay 603 to ground. Relay 616 energizes and 35 locks up through its contact and right-hand armature and the inner right-hand normal contacts of relay 614 to ground on the conductor 429. Upon the energization of relay 613, the switch is stepped, as before, to engage the brush 606 with the terminal 620 and the ground on said brush from relay 40 603 is then extended through the outer left-hand armature and front contact of relay 612, left-hand armature and contact of relay 616, back contact and outer right-hand armature of relay 614, and the winding of 45 relay 615 to grounded battery. Relay 615 energizes and locks up through its front contact and inner left-hand armature to ground on the conductor 429. The second 50 digit of the two digit number is then dialed and the proper contact for the second digit located in the second group associated with brush 611 is connected to conductor 619. The circuit then functions in the same manner 55 as described in connection with the fourth digit of a four digit number. Should a three digit number be dialed, no contact in the second group associated with the brush 611 is connected with conductor 619 when the second series of impulses is sent. Relay 614, will, therefore, not energize at the end of the last mentioned series 60 of impulses and the switch will be stepped

to normal. The proper contact in the first 65 group associated with the brush 611 is connected to conductor 619, and the switch then operates as previously described in connection with three digit numbers.

The code switch may be made to operate 70 to light the line lamp 423 by the transmission of a single series of impulses. In this case, the proper contact in the first group associated with brush 608 is connected to conductor 617 and the corresponding contact 75 in the first group associated with brush 610 is connected to the left-hand winding of relay 614. When relay 612 operates and locks up as before, ground is momentarily extended until relay 613 operates upon the release of relay 603, from the right-hand normal contacts of this relay through the brush 80 605, a terminal 621, armature and back contact of relay 613, conductor 618, contact engaged by brush 610 and from thence through the left-hand winding of relay 614 to grounded battery. Relay 614 then operates as before to light the line lamp 423. The switch is then stepped to engage the 85 brushes thereof with the intermediate vertical row of contacts, where the same stops until the trunk is released and relay 403 deenergized. The locking circuit of relay 612 is then opened and the latter relay releases 90 whereupon relay 613 is operated through the 95 back contact and outer left-hand armature of relay 612 to cause the switch to be stepped to normal in the same manner as previously described.

What is claimed is:

1. In a telephone system, a calling line, a switch having a normal position, a stepping relay for said switch, means responsive to impulses transmitted from said calling line for controlling the operation of said stepping relay, and means made effective by the first operation of said stepping relay in response to the first of a series of impulses for preventing said switch from moving from its normal position.

2. In a telephone system, a calling line, a switch for extending said line having a normal position, a stepping relay for said switch, means responsive to impulses transmitted from said calling line for controlling the operation of said stepping relay, means made effective by the first operation of said stepping relay in response to the first of a series of impulses for preventing said switch from moving from its normal position, and a circuit for said stepping relay controlled by the last named means after the first impulse of said series has been transmitted.

3. In a telephone system, a calling line, a switch having a normal position, a stepping relay for said switch, means responsive to impulses transmitted from said calling line for controlling the operation of said

- stepping relay and a relay short circuited by the first operation of said stepping relay in response to the first of a series of impulses for preventing said switch from moving 5 from its normal position.
4. In a telephone system, a calling line, a switch for extending said line having a normal position, a stepping relay for said switch, means responsive to impulses transmitted from said calling line for controlling the operation of said stepping relay, a relay made effective by the first operation of said stepping relay in response to the first of a series of impulses for preventing said switch 10 from moving from its normal position, and a circuit for said stepping relay controlled through contacts of the last named relay after the first impulse of said series has been transmitted.
5. In a telephone system, a calling line, a switch for extending said line, a stepping relay for said switch, means responsive to impulses transmitted from said calling line for controlling the operation of said stepping relay, a motor magnet for the switch controlled by said stepping relay, means made effective by the first operation of said stepping relay in response to the first of a series of impulses for preventing the operation 25 of said motor magnet, and circuits for said stepping relay and motor magnet controlled by the last named means after the first impulse of said series has been transmitted.
6. In a telephone system, a calling line, a switch for extending said line, a stepping relay for said switch, means responsive to the impulses transmitted from said calling line for controlling the operation of said stepping relay, a motor magnet for the switch controlled by said stepping relay, another relay made effective by the first operation of said stepping relay in response to the first of a series of impulses 30 for preventing operation of said motor magnet, and circuits for said stepping relay and motor magnet controlled through contacts of said other relay after the first impulse of said series has been transmitted.
7. In a telephone system, a calling line, a switch for extending said line having directive and automatic movements, a stepping relay for said switch, means responsive to the impulses transmitted from said calling line for controlling the operation of said stepping relay, a motor magnet for the switch controlled by said stepping relay during the directive movement of said switch, another relay made effective by 45 the first operation of said stepping relay in response to the first of a series of impulses for preventing operation of said motor magnet, circuits for said stepping relay and motor magnet controlled through contacts of said other relay after the first 50 impulse of said series has been transmitted.
- impulse of said series has been transmitted and during the directive movement of the switch, and another circuit for said motor magnet independent of said other relay effective during the automatic movement of 70 said switch.
8. In a telephone system, a subscriber's line, a trunk circuit, a switch for connecting said trunk circuit to said subscriber's line, means at said switch for normally preventing the connection of said trunk circuit to said line if the line is busy, means in said trunk circuit for operating the last named means to connect the trunk to the line during the busy condition of the latter, and means 75 operable when the line becomes idle to signal the same.
9. In a telephone system, a subscriber's line, a trunk circuit, a switch for connecting said trunk circuit to said subscriber's line, 80 a relay at said switch for normally preventing the connection of said trunk circuit to said line if the line is busy, a second relay operable upon the connection of said switch to the busy line to establish an energizing 85 circuit for the first named relay and means in said trunk circuit normally preventing the energization of said first named relay when the circuit therefor is established and operable to permit of the energization of 90 said first named relay whereby said trunk is connected to said busy line.
10. In a telephone system, a subscriber's line, a trunk circuit, a switch for connecting said trunk circuit to said subscriber's line, a relay at said switch for normally preventing the connection of said trunk circuit to said line if the line is busy, a second relay operable upon the connection of said switch to the busy line to establish an energizing 100 circuit for the first named relay, and means in said trunk circuit normally short circuiting the first named relay when the circuit therefor is established and operable to remove said short circuit to permit of the connection of said trunk to said busy line.
11. In a telephone system, calling and called lines, a switch for extending a connection from a calling line to a called line and having normal and intermediate terminals, a source of signaling current, a relay through which said source is connected to the calling and called lines, means for operating said relay when the switch is on said normal and intermediate terminals 105 whereby connection of said signal current to said calling line is prevented and other means operable to release said relay while the switch is passing over the other terminals.
12. In a telephone system, calling and called lines arranged in groups, a switch for extending a connection from a calling line to a called line the brushes of said switch having normal and intermediate posi- 115

- 125
- 130

tions, one of the intermediate positions being disposed between terminals allotted to groups of called subscribers' lines, a source of signaling current, a relay through 5 which said source is connected to the calling and called lines, means for operating said relay when the brushes of the switch are in said normal and intermediate positions whereby connection of said

signaling current to said calling line is 10 prevented, and other means operable to release said relay while the brushes of said switch are passing over terminals allotted to subscriber's lines.

In witness whereof, we hereunto subscribe 15 our names this 12th day of May A. D., 1921.

EDWARD E. HINRICHSEN.
SAMUEL B. WILLIAMS, JR.
